(57) **CLAIM**

I claim the ornamental design for wind power machine, as shown and described.

DESCRIPTION

FIG. 1 is a rear perspective view of a wind power machine showing my new design;

FIG. 2 is a front elevation view thereof;

FIG. 3 is a rear elevation view thereof;

FIG. 4 is a top plan view thereof;

FIG. 5 is a bottom plan view thereof; and,

FIG. 6 is a right side elevation view thereof, the left side view is a mirror image thereof.

The broken lines shown are for illustrative purposes only and form no part of the claimed design.
